UNITED STATES PATENT OFFICE.

AUBREY D. DAVID, OF CHICAGO, ILLINOIS, ASSIGNOR TO THE UNIVERSAL OIL PRODUCTS COMPANY, OF CHICAGO, ILLINOIS, A CORPORATION OF SOUTH DAKOTA.

PROCESS FOR CONVERTING PETROLEUM OILS.

Application filed February 14, 1923, Serial No. 619,038. Renewed April 24, 1928.

This invention relates to improvements in a process and apparatus for converting petroleum oils and refers more particularly to a process for the continuous destructive distillation of relatively high boiling point products to produce oils of a lower boiling point having the characteristics of gasoline.

Among the objects of the invention are to provide a process whereby provision is made for maintaining separated carbon particles produced during conversion in a suspended state and for diverting these suspended products to separate settling tanks to eliminate the necessity of shutting down the apparatus for frequent cleaning, due to the collection and accumulation of deposited carbon; to provide an apparatus for carrying out this process, and in general to provide a process and apparatus of the character referred to.

20. Fig. 1 is a diagrammatic side elevational view of the apparatus. Fig. 2 is a fragmentary plan view showing in detail the settling tanks.

Referring to the drawings at 1 is shown a furnace in which are mounted heating coils 2. The expansion tank 3 is connected to the heating coils by means of a transfer line 4 in which is interposed a valve 5. The expansion or vaporizing tank is connected by means of a vapor line 6 to a dephlegmator 7 which in turn communicates through the line 8 with a condenser coil 9 mounted in a water condenser box 10. The discharge end of the condenser coil communicates through a line 11 with the receiving tank 12 in which the liquid distillate produced in the system is collected. The dephlegmator has a lower leg 7a connected by a pipe 13 controlled by a valve 14 to the charging line 15 which communicates with the heating coils 2. At 17, 18, and 19 are shown settling tanks which are connected with a common header 20 which has connection with the expansion or vaporizing chamber 3 through the drawoff line 21 controlled by the valve 22.

45. Explaining now the treatment of the oil and its passage through the apparatus, the charging stock is introduced from any convenient source through the line 15 regulated by the valve 23, and is circulated through the heating coils 2 where it is raised to a conversion temperature after which it passes through the transfer line in the expansion chamber where it is collected in a considerable body, during which time the conversion and 55 vaporization of the oil takes place.

In the expansion chamber is a circular baffle member 24 positioned at a diagonal and adapted to facilitate the swirling circulation of the oil as is hereinafter explained. Try-cocks 25 are tapped into the side of the chamber in order to ascertain the liquid level therein. Separate drawoff lines 26 controlled by valves 27 supply a means for withdrawing the unvaporized oil from the expansion chamber in case the drawoff lines to the settling tanks 60 become clogged or obstructed for any reason. A drawoff line 28 controlled by a valve 29 is connected to the suction side of the pump 30. The discharge side of this pump is connected through a line 31 in the side of the chamber 65 in a manner to produce a swirling action of the liquid oil body in the chamber due to the introduction of liquid products circulated through the pump 30.

The purpose of this local circulation is to 75 maintain the oil body in the chamber in a turbulent condition in order that the free carbon separated during the conversion or vaporization of the oil will be held in suspension in the liquid residual substances which are 80 drawn off through the line 21 and directed to the separate settling tanks 17, 18 and 19 through the header 20 and connections 32, 33 and 34 communicating with the respective tanks.

The tanks are equipped with try-cocks 35 for ascertaining the oil level therein. These tanks may be cut in and out as desired, and the residual products permitted to collect therein where the oil in stagnant condition permits the separation of its solid content.

Three tanks are shown in the drawing, but it is understood that any number of tanks may be used according to the amount of oil treated and the amount of carbon that is necessary 90 to be eliminated from the residual liquid withdrawn from the expansion chamber.

At the opposite end of the tanks are draw-off lines from the separate chambers controlled by valves 36 which communicate with the common header 37. The liquid oil withdrawn through this line may be directed to any convenient storage not shown, or to further treatment as desired.

The tanks are constructed so that they may be isolated from the system and the manhole plates at the end removed so that they may be readily cleaned of the deposited carbon.

The local circulation of the liquid products from the expansion chamber through the 110

pump 30 and back into the expansion chamber assures a turbulent condition of the oil during the vaporizing or conversion period. This turbulency not only maintains the carbon particles in suspension, but also promotes the evolution of the vapors.

It will be readily appreciated by this mode of operation, the apparatus may be operated over a considerable longer period of time, due to the fact that the carbon is collected and separated in separate settling tanks which may be cut out of the system for cleaning, if desired.

A further advantage is the fact that the oil during its period of conversion in the evaporating chamber, is maintained in a turbulent condition which increases the cracking action.

By treating mid-continent gas oil to temperatures from 700° to 900° F., and at pressures from 50 to 300 pounds, a good quality distillate of approximately 50° Baumé is obtained, and the apparatus can be operated continuously for a much longer time than as heretofore has been possible; due to the fact that carbon deposited is practically eliminated from the system. The apparatus is particularly adapted to conversion of heavy carbon laden oils such as Texas and Mexican oils, and fuel oils due to the fact that these petroleum products are heavily carbon laden, which is easily separated out at high temperatures.

I claim as my invention:

35. 1. A process for treating hydrocarbon oil consisting in raising the oil to a cracking temperature while advancing in a stream through a heating zone, in transferring the highly heated oil to an enlarged reaction 40 chamber wherein a substantial body of oil accumulates and wherein no rise in oil temperature occurs, in taking off vapors from said enlarged chamber for condensation and collection, in continuously withdrawing residual oil from said enlarged chamber without recirculating any portion thereof through said heating zone, in maintaining a swirling

motion of the liquid oil in said enlarged chamber to hold the carbon in suspension in the oil by withdrawing a portion of the liquid oil therefrom and returning it under an increased pressure to said chamber tangential to the wall thereof.

2. A method for preventing the accumulation of solid coke-like deposits in the reaction chamber of an oil cracking apparatus of the continuous type, in which the oil is heated in a coil, thereafter delivered to a reaction chamber, wherein the oil separates into vapors and unvaporized residue, which comprises continuously removing a portion of the liquid residue from the reaction chamber and isolating such removed portion of the liquid residue from the apparatus, continuously removing an additional portion of the hot unvaporized liquid residue from the reaction chamber, placing said last mentioned portion of the hot residue under a mechanically imposed pressure and re-introducing the same, under such mechanically imposed pressure, into said reaction chamber, below the liquid level of the oil therein, but above the point of removal of the liquid residue from said reaction chamber, and so re-introducing such additional portion of the hot liquid residue into said reaction chamber that a swirling motion is imparted to the oil body therein, whereby coke-like particles resulting from the cracking reaction are held in suspension until removed from the reaction chamber with that portion of the residue which is isolated from the apparatus.

3. An improvement in a method for cracking hydrocarbon oil of the type in which the oil is heated in a coil and thence transferred to an enlarged reaction chamber wherein a body of oil accumulates, comprising maintaining a swirling motion of the liquid oil in said enlarged chamber to hold the carbon in suspension in the oil by withdrawing a portion of the liquid oil from the chamber and returning it under an increased pressure to said chamber tangential to the wall thereof.

AUBREY D. DAVID,
